UNITED STATES PATENT OFFICE.

REINHARD MANNESMANN, OF BLIEDINGHAUSEN, REMSCHEID, GERMANY.

METHOD OF PRODUCING PRESSURE-TENSION IN TUBULAR BODIES.

SPECIFICATION forming part of Letters Patent No. 440,489, dated November 11, 1890.

Application filed July 21, 1890. Serial No. 359,382. (No model.)

To all whom it may concern:

Be it known that I, REINHARD MANNESMANN, a subject of the Emperor of Germany, residing at Bledinghausen, Remscheid, Germany, have invented a new and useful Improvement in the Method of Producing Pressure-Tensions in Tubular Bodies, of which the following is a specification.

Referring to the drawings, Figure I is a longitudinal axial section of what is known as a "built-up gun," and Figs. II to V are diagrams illustrative of the direction of forces in the process of construction.

The invention relates to the construction of ordnance, and has for its object the production of guns of greater strength relatively to the caliber and weight of metal than it has heretofore been possible to produce.

The invention consists in a method or process of construction as will now be fully described.

According to the well-known Uchatius process, the bored bronze gun-tubes are treated in such a manner as that they will be subjected to interior pressure and exterior traction, the two forces being applied simultaneously in order to obtain a homogeneous tube. This method or process has, however, disadvantages, in that it is difficult to uniformly apply the two forces acting in a direction at right angles to each other upon the metal, and still more difficult to regulate or vary these forces with a view to regulate or vary the pressure and traction tensions. My invention is designed to overcome these difficulties and accomplish the desired ends in a manner not only more simple and economical, but also more efficient, and my method or process is based upon the contractility of heated metals when acted upon by a cooling agent and upon the simultaneous application of pressure.

If a heated tubular metallic body is cooled from the interior, the inner stratum in contact with the cooling agent will contract, while the outer hot stratum will retain its form. In the act of cooling and contracting of the inner stratum of metal radial forces are developed that tend to separate the cooler from the hotter portions of the metal, as indicated by arrows, Fig. II. As the cooling from the interior toward the exterior proceeds, the zone

at which the cooler portions of the metal tend to separate from the hotter portions is shifted accordingly—that is to say, this zone of tendency to separation moves outwardly as the cooling proceeds in that direction, until finally it vanishes at the periphery when the body has been uniformly cooled, as shown by arrow, Fig. III, nearly all of the tension due to the cooling vanishing also; but if pressure is applied from the exterior of the tubular body and caused to act upon the metal simultaneously with the cooling agent the metal acted upon by pressure is made to follow up the radial tractional force exerted in the inner cooled portions of such metal, as shown by the arrows in Fig. IV, so that these tractional forces will vanish with the zone of tendency to separation. As soon as the external compressing force ceases to act upon the tubular body the compression-tension will also vanish or cease in that portion of said tubular body influenced by said force, and upon cooling the said portion will contract but little, if at all. It follows from the above that a tractional force will be developed in the outer portions of the metal, while pressure-tensions will be developed in the interior portions, as shown by arrows, Fig. V. The external pressure may be applied by any desired means—such as the hammer—or by means of rolls or hydraulic or other press. In fact, any mechanical appliance by means of which the desired pressure can be applied may be used.

As the tubular body is cooled and contraction in the metal proceeds, the cooled and contracted portions offer a greater resistance to change of form than the hotter outer portions of the metal, so that the said inner cooled portions or strata will acquire a pressure-tension while the tubular body is being worked exteriorly and cooled interiorly, which (tension) will increase materially with the cooling off and consequent contraction of the outer portions of the metal. Now, if the exterior pressure is continued while the cooling from the interior proceeds, the interior pressure-tensions and the exterior traction-tensions will increase, thereby bringing the metal of the tubular body into more intimate union, producing a perfectly homogeneous body capable of resisting great internal pressures.

In Fig. I, I have illustrated a gun-tube of

that class known as "built-up guns," and composed of a plurality of concentric tubes *a, b, c, d, e, and f*. The phenomena that will take place when such a tube is heated to the proper temperature, then subjected to external pressure, and simultaneously therewith cooled interiorly by the admission to the bore of a suitable cooling agent fed thereto through pipe A, will be readily understood from what has been said above. It is evident, therefore, that the process or method is applicable to tubular bodies, whether such are built up of a plurality of concentric tubes or of a single tube. If a built-up tube is heated and subjected to external pressure and simultaneously therewith cooled interiorly, the inner tubes will be subjected to pressure and the outer ones to traction. When such a tube is subjected to high internal pressure, the interior diameter will slightly increase, and when said internal pressure has reached a given degree the pressure-tension in the inner tubes will be converted into traction-tension, so that all of the tubes will then be subjected to traction-tension.

From the description of the method or process it will readily be seen that the tensions in the different strata of the tubular body may be determined, more especially the proportional radial pressure-tension exerted from the interior of the tubular body and its transition into traction-tension, so that according to the nature and degree of the internal pressure to which the tubular body may finally be subjected the zone of no tension may be removed farther from or brought nearer to the inner surfaces of such body on the one hand, and on the other it will be possible to impart to the metal adjacent to the interior stratum a suitable pressure-tension. This may be effected by simply regulating the degree to which the tubular body is heated and the degree to which it is cooled interiorly during the manipulation of such body.

Any suitable cooling agent may be employed, either solid, liquid, or gaseous, and I would have it understood that I do not limit myself to any particular cooling agent or to the means of applying the same; nor do I desire to limit myself to any particular means

for applying the external pressure, which, as above stated, may be of any suitable character.

Finally, it will be readily understood that the process or method is not only applicable to the construction of ordnance, but also to the construction of the tubes or barrels of small fire-arms, and to the construction in general of all cylindrical hollow bodies as are subjected to great internal pressures in practical use—such, for instance, as the cylinders of hydraulic presses, and so on.

Having thus described my invention, what I claim, and desire to secure by Letters Patent, is—

1. The herein-described improvement in the construction of tubular bodies, which consists in producing a shrinkage of the interior walls of the tubular body and in causing the remaining metal to follow up such shrinkage by applying external pressure for the purposes specified.

2. The herein-described improvement in the construction of tubular bodies, which consists in introducing a cooling agent into the tubular body while in a heated condition and simultaneously therewith subjecting the said body to external pressure.

3. The herein-described improvement in the construction of tubular bodies, which consists in subjecting a bundle of concentric tubes to external pressure while in a heated condition and in simultaneously cooling said bundle of tubes from the interior.

4. The herein-described improvement in the construction of gun tubes and barrels, which consists in forming a bundle by telescoping a plurality of tubes having comparatively thin walls, in uniting the tubes by subjecting the bundle to external pressure while in a heated condition, and in simultaneously cooling the said bundle by introducing a cooling agent into the inner tube thereof.

In witness whereof I have hereunto set my hand in the presence of two attesting witnesses.

REINHARD MANNESMANN.
